[57] CLAIM

The ornamental design for a dental implant, as shown and described.

DESCRIPTION

FIG. 1 is a front elevational view of a dental implant showing our new design;

FIG. 2 is a top plan view thereof;

FIG. 3 is a bottom plan view thereof;

FIG. 4 is a side elevational view thereof, the opposite side being a mirror image;

FIG. 5 is a cross-sectional view thereof, taken on line V—V in FIG. 1;

FIG. 6 is a cross-sectional view thereof, taken on line VI—VI in FIG. 1;

FIG. 7 is a cross-sectional view thereof, taken on line VII—VII in FIG. 1;

FIG. 8 is a cross-sectional view thereof, taken on line VIII—VIII in FIG. 1; and,

FIG. 9 is a top perspective view thereof.

FIG. 4
